DISCONNECT SWITCH

Howard F. Burmeister, Harvey, Ill., assignor to
 Royal Electric Manufacturing Co., Chicago, Ill.,
 a corporation of Illinois

Application September 21, 1949, Serial No. 117,018

6 Claims. (Cl. 200—82)

1

This invention relates primarily to disconnect switches, particularly of the high voltage type.

It is one of the objects of the present invention to provide a vertical break disconnect switch of the type wherein the movable switch member is mounted on a stationary insulator and wherein the actuation of the movable switch member is obtained pneumatically or hydraulically by a pneumatic mechanism at the potential of the movable switch member, so that no mechanically moving insulators must be provided for transmitting the thrust required to actuate the movable switch member. This eliminates one of the three insulators usually provided on vertical break disconnect switches.

In accordance with the preferred embodiment of the present invention a pneumatic mechanism, which may consist of a piston and cylinder arrangement, preferably a double acting cylinder, is mounted on the structure that supports the switch blade, the pneumatic mechanism being at the potential of the switch blade. Fluid under pressure is transmitted to the cylinder for actuating the same by way of one or two tubes that extend thereto. These tubes include, in a stationary portion thereof, an insulated section thereby insulating the pneumatic mechanism from the operator. This section, in the preferred construction, is the sole insulator that supports the switch blade.

High voltage ceramic insulators which are of considerable size have been made hollow. Such hollow ceramic insulators have been provided with end caps at opposite ends thereof, the end caps being drawn firmly towards the insulator by a tensioning member of insulation within the hollow body of the ceramic insulator, the remaining interior of the insulator being then filled with an insulating oil to assure exclusion of all air and moisture. Such an insulator is shown in the patent to Arthur O. Austin, No. 2,175,836, of October 10, 1939. It is one of the objects of the present invention to utilize such an insulator to support a switch blade of a disconnect switch and to utilize the hollow space within the insulator for transmitting fluid under pressure to a pneumatic mechanism at the high voltage end of the insulator, namely, at the end of the insulator that carries the switch blade. The pneumatic mechanism mechanically operates the switch blade.

It is a further object of the present invention to provide the end caps of a hollow insulator of the above mentioned character with one or more nipples, corresponding nipples of the two end

2

caps being connected by a tube of insulation that extends from one end cap to the other through the hollow insulator. Each of these insulating tubes is surrounded by the insulating oil or other compound within the insulator and in turn also carries an insulating fluid. As a result, oil or other insulating fluid may be transmitted through the tube or tubes for performing necessary mechanical operations, as, for instance, operating a switch. The hydraulic control system of which the tubes are a part are entirely separate from the liquid insulation within the hollow ceramic insulator.

It is a further object of the present invention to provide a hollow insulator with means for transmitting actuating force to actuate the electrical apparatus and wherein the same insulator that supports the apparatus also provides insulation in the hydraulic circuit to the control apparatus.

The attainment of the above and further objects of the present invention will be apparent from the following specification taken in conjunction with the accompanying drawings forming a part thereof.

In the drawings:

Figure 1 is an enlarged fragmentary sectional view of a portion of a high voltage disconnecting switch embodying the present invention;

Figure 2 is a sectional view taken along the line 2—2 of Figure 1 and looking in the direction of the arrows;

Figure 3 is a small scale drawing showing the switch part of which is shown in Figure 1; and

Figure 4 is a diagrammatic view showing one manner of hydraulically interconnecting the switches of a three phase system for simultaneous operation.

Reference may now be had more particularly to the drawings wherein like reference numerals designate like parts throughout.

A general description will first be given of the switch of Figure 3. This switch is an outdoor type, vertical break disconnect switch. This switch, indicated in general by the reference numeral 1, includes a mounting base 2 of channel iron or the like, of a conventional construction, on which are mounted two stationary insulators, indicated at 3 and 4. The stationary insulating structure 3 supports a contact structure 5 that is adapted to be engaged by a switch blade 6 that is pivoted at 7 to a bracket 8 mounted on the insulator 4. The contact structure 5 mounted on top of the insulator 3 may be of any preferred construction, the one illustrated being

that of the patent to Dunlap, No. 2,306,117, to which reference may be had. It is sufficient here to state that the contact structure comprises a contact base 10 that is bolted or otherwise secured to the insulator 3 and includes a line terminal lug 11 to which a line conductor is connected. Pivoted on the contact base 10 is a contact rod bracket 13 that carries a number of spring contact wires 16 that are adapted to receive between them the end of the blade 6 which moves the contact rod bracket 13 from the dotted line switch open position to the full line switch closed position. In addition, the bracket 3 carries an arcing horn 15 that cooperates with an arcing horn 16 on the blade 6, all in a manner conventional in the art. The insulator 3 may be of any desired construction, one preferred construction being that illustrated in the patent to Austin, No. 2,175,363.

The stationary insulator 4 is a hollow type ceramic insulator, preferably of the general type shown in the patent to Austin above referred to. This insulator includes a hollow body of ceramic insulation 20 the upper and lower ends of which are perfectly smooth and are overlaid by upper and lower metal end caps 21 and 22, respectively. The lower end cap has an inwardly extending projecting clevis 23 that supports a pin 24, and the upper end cap 21 has an opening through which extends an eye bolt 24 that supports a pin 25. A belt 26 of insulation is wound around the pins 24-25 and by tightening of the nut on the eye bolt 24 the belt of insulation is tensioned, thereby compressing the ceramic insulation 20 and firmly securing the end caps 21-22 thereto in sealing relationship. A pair of nipples 28-29 are mounted on the under side of the upper end cap 21 and a similar pair of nipples 31-32 are mounted on the upper side of the lower end cap 22. The nipples 33-34 and 31'-32' are sealed around their junction with the end caps to avoid leakage between the hollow body of the insulator and the outside of the insulator through the space between the nipples and the end caps. The nipple 28 is connected to the nipple 31 by a tube 35 of suitable insulation, and the nipple 29 is connected to the nipple 32 by means of a similar tube of insulation 36. The upper nipples 29-29 communicate through ports in the end cap 21 with nipples 33-34 that extend from the sides of the cap 21, and the lower nipples 31-32 communicate through ports in the cap 22 with nipples 31'-32', respectively, that extend radially from the sides of the cap 22. The two tubes of insulation 35 and 36 are arranged in a slight spiral within the body of the insulator in order to avoid tensioning of the tubes and to increase the electrical creepage paths along the surfaces of the tubes. The hollow insulator 20 is filled with an insulating oil or other insulating liquid in order to assure the exclusion of all air or moisture therefrom.

A blade supporting U-shaped bracket 43 is mounted on the end cap 21 as by four bolts 41 that thread into tapped bores in the top of the end cap 21. A blade carriage 42 in which the blade 6 is mounted is pivoted on the bracket 43 in any desired manner, as by the pivot pin 7, the carriage being rigidly clamped to the pin by sets of bolts 45. A line terminal lug 46 is secured to the bracket 43 in any desired manner and carries six copper clad spring contact wires 47 arranged in two rows of three wires each, said wires being on opposite sides of the pivot pin 7 and in firm pressure engagement therewith to extend the circuit from the terminal 46 to the pin 7 and

through that pin to the carriage 42 and the switch blade 6.

The switch blade is adapted to be swung about the center of the pin 7 from a switch closed position in which the blade is horizontal, through an angle of approximately 95° upwardly, to its switch open position. To effect this result the blade is provided with an actuating arm 49 bolted thereto which, at 53, provides a pivot connection to a connecting rod 51 that extends to a hydraulic mechanism 52. The hydraulic mechanism comprises a double acting cylinder 53 pivoted to the bracket 40 by a pivot pin 55. A piston 56 reciprocates within the bore of the cylinder 53. The connecting rod 51 extends into the cylinder 53 through suitable packing and is connected to the piston 56. Pressure for operating the piston 56 in one direction is transmitted to the cylinder by way of a bore 59 and a nipple 58. Pressure for operating the piston in the reverse direction is transmitted through a nipple 60, a bore 61 and a bore 62. The nipple 58 is connected through a tube 65 to the nipple 33 and the nipple 60 is connected through a tube 66 to the nipple 34.

From the above description it is apparent that by applying hydraulic pressure to the nipple 31 that pressure is transmitted by way of the tube 35 within the insulator 20 and the tube 65 to the portion of the cylinder 53 on the left hand side of the piston 56, which results in operation of the piston 56 to the right as seen in Figure 1. The movement of the piston is transmitted through the connecting rod 51 and the pivot 53 to the switch blade thereby swinging the switch blade to its switch open position. At the same time oil or the other fluid that is used for operating the pneumatic mechanism 52 is expelled from the portion of the cylinder 53 to the right of the piston 56, thence through the tube 66, nipple 34 and tube 66 to the nipple 32.

The oil pressure is applied to the nipples 31-32 selectively, for producing the desired operation of the switch, in any desired manner. By way of illustration, there is shown here a hydraulic operating mechanism comprising a master cylinder 73 having therein connected pistons 71-72 adapted to be reciprocated by a handle 73 pivoted to the cylinder casing by a shaft 74 to which the handle is keyed on the outside of the casing, said shaft extending into the cylinder casing and having keyed thereto on the inside of the casing a crank 75 that has a pin and slot connection with a piston rod 76 that connects the two pistons. The cylinders on opposite sides of the pistons are connected by copper oil tubes 78-79 to the nipples 31'-32', respectively. It is thus apparent that actuation of the handle 73 results in movement of the pistons 71-72 to force oil into one of the lines 78-79 while the cylinder receives oil from the other line. The pistons 71-72 are of slightly different areas, the ratios of the areas being the same as the ratios of the effective piston areas on opposite sides of the piston 56. The effective areas on the two opposite sides of the piston 56 are different, due to the fact that the area of the piston rod 51 is subtracted from the effective area on one side of the piston 56.

It is understood that any desired operating mechanism may be provided for supplying oil under pressure selectively to one or other of the lines 78-79 for actuating the switch, the particular construction here shown being merely illustrative. Also, while I have shown herein structures wherein the hydraulic operating mech-

anism consists of a piston and cylinder arrangement, it is understood that the piston and cylinder arrangement may in each case be replaced by a hydraulic diaphragm mechanism or by a hydraulic expansion bellows so that the oil pressure system for operating the switch in one direction is completely sealed from the oil pressure system for operating the switch in the opposite direction, without the possibility of leakage from one to the other, such as may occur past the piston 56 or past the pistons in the mechanism 75.

In the hydraulic system herein shown there is a complete separation of the oil to be used for operating the switch from the body of oil within the bore of the insulator 20. Where a complete separation is not necessary then one or the other of the two tubes 35—36 may be entirely omitted. If, for instance, the tube 35 is omitted then the bore of the insulator 20 acts as a connection from the nipple 28 to the nipple 31. If the tube 36 is omitted then the bore of the insulator acts as an oil connection between the nipple 29 and the nipple 32 so that in either event the oil for operating the switch in one direction is transmitted bodily through the bore in the insulator 20.

I have herein shown the present invention as applied to operate a vertically operating switch blade of a disconnecting switch. Since the invention is particularly concerned with the operating mechanism, I have herein omitted some of the usual disconnecting switch structures. For instance, switch blades are generally provided with counterbalancing springs for assisting in the switch opening operation and for holding the switch blade in the switch open position. This may be applied to the switch blade of the present invention in any conventional manner, as, for instance, as shown in the patent to Dunlap, No. 2,306,117, above referred to.

In some instances the double acting piston in the cylinder 52 may be replaced by a single acting piston wherein pneumatic pressure is applied for moving the switch in one direction, say, in the switch closing direction, and a spring is provided for moving the switch in the switch opening direction. This may be the usual blade counterbalancing spring shown in the above mentioned Dunlap patent, which spring is then made stiffer so that the spring itself is capable of moving the switch from the switch closed position to the switch open position, the pneumatic pressure being relied upon to move the switch to its closed position and hold it in that position. When that is the case only one pneumatic line need be extended from the operating mechanism 75 to the pneumatic mechanism 52. That line can extend via a tube through the insulator 20, as above mentioned, or the tube within the insulator 20 may be entirely omitted so that the bore of the insulator 20 itself constitutes a part of the oil conduit to the pneumatic mechanism.

In each embodiment above described the insulator 20 constitutes the sole support for the switch blade and also affords a passageway for the oil used for actuating the pneumatic mechanism at the top of the insulator. By this arrangement the switch actuating means 75 which is at ground potential may be placed at any convenient location.

In a three phase system where three disconnect switches of the type shown in Figure 1 are provided, they may be arranged for simultaneous operation, the pneumatic circuit at the grounded ends of the switches being a series circuit, as illustrated in Figure 4. In Figure 4 there is shown at

A, B and C, in diagrammatic form, a portion of each of the three disconnecting switches each one of which may be physically of the same construction as is illustrated in Figure 3. The blade supporting insulator of each switch is indicated by the reference numeral 4, that insulator being of the same construction as illustrated in Figures 1, 2 and 3. The pneumatic mechanisms that are mounted on the respective insulators 4 are indicated at 52a, 52b and 52c, being in each case connected to operate the respective switch blades 6. Each pneumatic mechanism includes a cylinder 53, a double acting piston 56 and a connecting rod 51 for operating the switch blade 6 in the manner previously described. In order that the volume of liquid displaced on each side of the piston may be the same for a given distance of movement of the piston the piston 56 is in each case provided with a false piston rod 51' of the same diameter as the piston rod 51, which false piston rod slides through suitable packing in the end of the cylinder. A suitable seal is provided for sealing against the escape of any oil from the cylinder at the place where the false rod 51' extends therethrough. The nipples 31'—32' of the three insulators are connected in series by oil tubes 85 and 86 and the series circuit is connected to the oil lines 78—79 that extend to the manual or motor operating mechanism 70, as previously described. From this description it is apparent that transmission of the oil under pressure to the line 78' to operate the switches will force oil to the left hand side of the piston 56 of the A phase switch to move that piston, and the movement of that piston will force oil from that portion of the cylinder 52a which is to the right of the piston 56, thence through the tube 66, tube 36 of the A phase insulator 4, thence through the tube 85 to the B phase insulator for actuating the pneumatic mechanism 52b. This in turn transmits operating fluid in the same manner to the C phase pneumatic mechanism 52c. By making a positive provision against leakage in the oil system and by using tubes and connections which are of constant volume and will not expand under pressure it is thus possible to operate all three switches simultaneously.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. A two insulator outdoor type disconnect switch comprising a stationary hollow insulator, a contact making member supported thereby, a double acting hydraulic mechanism also supported thereby, means connecting the mechanism with the contact making member for operating the contact making member, separate hose means providing separate fluid passageways extending to opposite sides of the mechanism for supplying liquid to the mechanism for actuating it, each of said hose means extending through the hollow supporting insulator, a filling of liquid insulation within the insulator and through which insulation the hose means extends but is sealed therefrom, end caps for said insulator sealing said filling of liquid insulation from the atmosphere, said fluid passageways extending through the sealing end caps, a second insulator spaced from the first insulator, means for supporting the second insulator independent-

ly of and apart from the first insulator, and a contact member supported by the second insulator and adapted to be engaged by the contact making member in its switch closed position.

2. In combination, a number of similar high voltage switches each switch comprising a hollow insulator, a switch contact making member on said insulator and movable from the switch open position to the switch closed position, means for actuating the member including a hydraulic motor mechanism on said insulator, a pair of hydraulic lines extending to the motor mechanism for supplying it with liquid under pressure to operate it in alternate directions, said lines extending through the insulator from the high voltage side thereof to the low voltage side thereof; the lines of the respective switches on the low voltage side thereof being connected in a closed series fluid circuit, and means for applying pressure to cause flow of fluid in the fluid circuit selectively in one direction or the other to cause simultaneous operation of the hydraulic motors of the respective switches.

3. In combination, a number of similar high voltage switches each switch comprising a hollow insulator, a switch contact making member on said insulator and movable from the switch open position to the switch closed position, means for actuating the member including a hydraulic motor mechanism on said insulator, a pair of hydraulic lines extending to the motor mechanism for supplying it with liquid under pressure to operate it in alternate directions, said lines extending through the insulator from the high voltage side thereof to the low voltage side thereof; the lines of the respective switches on the low voltage side thereof being connected in a series fluid circuit, and means for supplying liquid under pressure to the circuit to cause simultaneous operation of the hydraulic motors of the respective switches, said last named means including means for selectively controlling the direction of flow of fluid in said fluid circuit.

4. In a polyphase switching system a plurality of disconnect switches for the respective phases each including a hydraulic operating mechanism at the high potential side of the switch, liquid operating circuits for the respective mechanisms, and means connecting the liquid operating circuits of the respective switches in series.

5. In a polyphase switching system a plurality of disconnect switches for the respective phases each including a hydraulic operating mechanism at the high potential side of the switch and a hollow insulator supporting the mechanism, liquid operating circuits for the respective mechanisms, the liquid circuit for each mechanism extending through the insulator of its switch, and means connecting the liquid operating circuits of the respective switches in series.

6. An insulator comprising a hollow column of insulation, end caps closing the ends of the column, a switch blade, means on one end cap pivotally mounting the switch blade for swinging movement from switch open position to switch closed position, hydraulic mechanism for swinging said blade, a filling of liquid insulation within the column and closed off from the outside atmosphere by the caps, and a pair of insulating tubes extending within the column from one end cap to the other, the two end caps having outlets for the tubes for establishing liquid passageways through the tubes but sealed from the filling of insulation within which the tubes are immersed and a fluid flow connection between said tubes and said hydraulic mechanism.
